CLAIM

The ornamental design for an enclosed reflex sight as shown and described.

DESCRIPTION

FIG. 1 is a top front perspective view of an enclosed reflex sight showing my new design;

FIG. 2 is a front view thereof;

FIG. 3 is a back view thereof;

FIG. 4 is a left side view thereof;

FIG. 5 is a right side view thereof;

FIG. 6 is a bottom view thereof;

FIG. 7 is a top view thereof;

FIG. 8 is a top back perspective view thereof;

FIG. 9 is a top back perspective view thereof;

FIG. 10 is top back perspective view thereof; and,

FIG. 11 is top back perspective view thereof.

The broken lines in the drawings depict portions of the enclosed reflex sight that form no part of the claimed design.

The broken lines of a firearm mounting interface of FIG. 8 and FIG. 9 are illustrative of environment and form no part of the claimed design. The broken lines of the firearm mounting interface and pistol slide of FIG. 10 and FIG. 11 are illustrative of environment and form no part of the claimed design.

1 Claim, 9 Drawing Sheets
